UNITED STATES PATENT OFFICE.

VICTOR E. EDWARDS, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

ROLLING-MILL.

1,278,617.

Specification of Letters Patent. Patented Sept. 10, 1918.

Original application filed August 2, 1915, Serial No. 43,132. Divided and this application filed November 9, 1916. Serial No. 130,494.

To all whom it may concern:

Be it known that I, VICTOR E. EDWARDS, a citizen of the United States, residing at Worcester, in the county of Worcester and 5 Commonwealth of Massachusetts, have invented a new and useful Improvement in Rolling-Mills, of which the following, together with the accompanying drawings, is a specification, the present application being a division of my copending application 10 Serial No. 43,132, filed August 2, 1915.

The present invention relates to a rolling mill and has particular reference to a construction employed for directing cooling water against the operating surfaces of the rolls of such a mill. The invention is here shown in connection with a construction embodying two stands of reducing rolls disposed in a single housing, the said construction 15 being applicable to the method of rolling "rounds" fully set forth and described in my Letters Patent of the United States No. 1,193,001, granted August 1, 1916; but it is to be understood that my invention is applicable 20 to any and all types of reducing rolls and is not confined in any sense to employment with rolls disposed in stands such as herein shown and described.

My invention is fully set forth in the following 25 description, reference being had to the accompanying drawings, in which—

Figure 1 is a side elevation, partially in vertical section, of the roll housing to which my invention is here shown as applied, and 30 Fig. 2 is a horizontal sectional view thereof on the line 2—2, Fig. 1.

Similar reference characters refer to similar parts in both figures.

Referring to the drawings, as showing a 35 mechanism of the type set forth and described in my aforesaid copending application, 1 indicates a pinion housing which serves for the support of a roll housing 2, the latter carrying both the vertical and the horizontal stands of rolls above referred to. The said roll housing, for convenience of description, may be considered as being divided roughly by a transverse wall 3 into two compartments, one, 4, containing the 40 stand of vertical rolls 5, 5, and the other,

6, containing the stand of horizontal rolls, 7, 7. The compartment 4 is defined by side walls 8, 8, joined together at the top and bottom by transverse upper and lower front walls 9, 10, which have a rectangular opening 11 between them. The compartment 4 thereby presents separated upper and lower substantially inclosed recesses, which are designed to contain respectively the upper and lower pairs of bearings 12, 12 and 13, 13 55 for the necks of the vertical rolls 5, 5.

The compartment 6 of the roll housing 2, containing the pair of horizontal rolls 7, 7, is defined roughly by a pair of spaced upright walls 14, disposed parallel to and at a distance from the partition 3. In the recesses thus formed at each side of the housing, the bearings 15, 15 and 16, 16 for the necks of rolls 7 are received. In the rectangular opening 11, between the front walls 70 9, 10 of the housing, is supported a fixed receiving guide 17 for the metal, said guide projecting inwardly into juxtaposition with the pass of the vertical rolls 5, 5. The partition 3 supports a fixed intermediate guide 75 18 adapted to convey the metal from the pass of the vertical rolls to the pass of the horizontal rolls 7. These two guides are in axial alinement with each other, and also with a third fixed delivery guide 19, supported by a plate 20 which is attached to the rear walls 14 which inclose the bearings 15 and 16 of the horizontal rolls. The longitudinal or axial adjustment of the rolls, each of which has the usual series of peripheral grooves coöperating to form passes of various sizes, will now be described, it being understood that the said adjustment is effective not only in bringing a pass into proper alinement with the fixed guides 17, 80 18 and 19, but also in rendering possible the substitution of various passes, without removal of the rolls from their bearings and without disconnecting the driving shafts of said rolls from the shafts of the driving pinions. Since the axial adjustment devices for all the rolls of the two stands of rolls are identical, a description of the same with respect to the vertical rolls will suffice 85 for the horizontal rolls.

The walls of housing 2 provide, adjacent the outer end of each roll bearing 12, 13 15 and 16, a plurality of notches 21. Adjusting yokes 22 and 23, disposed at opposite 5 ends of each vertical roll, provide projecting curved ears 24 adapted for reception within said notches to afford the fulcrums for each yoke. The inner face of each yoke provides raised projections 25 adapted to bear 10 against the outer end of the adjacent bearing. The free end of each upper yoke 22 is slotted for the passage of a fixed rod 26, carried by the housing, on the upper end of which a washer 27 is pressed against the 15 yoke 22 by adjusting nuts 28. The downward movement of said nuts rocks the yoke downwardly, Fig. 1, to carry the upper bearing 12 in the same direction. Each lower yoke 23 has connected thereto a sliding rod 29, by means of pins 30, which limit 20 relative movement between rod and yoke. The upper end of said rod 29, projecting beyond the housing, carries adjusting nuts 31, by means of which the inward movement 25 of the lower bearing 13 is secured. The adjusting devices of the two bearings are thus located conveniently at one end of the roll, and the inward adjustment of each bearing is made dependent upon the amount 30 by which the adjustment of the device of the other bearing is loosened, that is, when a roll 5 is to be adjusted downward, the retaining rod for its lower yoke 23 is loosened an appropriate amount, and then the upper yoke 35 22 is drawn downwardly a corresponding amount, both of these adjustments being performed at the top of the housing. The yokes 22 for the two bearings of each horizontal roll have the same adjustment devices 40 as described above.

Referring to Fig. 1, the vertical roll 5 shown therein provides, in the present instance, four peripheral grooves 32, 33, 34 and 35, the roll being so disposed axially as 45 to bring the groove 34 into approximate alignment with the guides 17, 18 and 19. In order to secure a delicate adjustment, the two yokes 22 and 23 are moved in or out by the adjusting nuts 28 and 31. In order to 50 bring the groove 35 into the same position as the groove 34, the yokes 22 and 23 are elevated to bring their ears 24 into the notches 21, just above those in which they are shown as located in Fig. 1. In the same manner, 55 each of the two other grooves 32 and 33 may be rendered available by removing the roll with its bearings 12 and 13 and replacing the same in a reversed position. It will be clearly understood that each roll of both 60 stands of rolls is longitudinally adjustable in precisely the same manner as above described, in order not only to render the different grooves of the same available to form the pass, but also to afford a delicate and ac-

curate alinement of each groove with the 65 guides 17, 18 and 19.

The adjustment and reversal of the rolls above described is permitted by reason of the novel driving means provided therefor, which is in all essential respects the same 70 for each roll and hence it will be sufficient to describe it in detail for one of the vertical rolls shown in Fig. 1. A pinion 36 is driven from a shaft 37, the latter being operatively connected to a source of power, 75 not shown. The pinion 36 provides a square opening for the reception of a square end 38 of a shaft 39, which projects through the yoke 23 and enters the roll 5. The said roll is bored out from end to end and then 80 squared, so that the square upper end 40 of shaft 39 is capable of imparting rotation to the roll in all positions of adjustment assumed by said roll. As shown in Figs. 1 and 2, the square openings in the roll and in 85 the pinion 36 are slightly larger than the squared ends of the shaft 39, so that sufficient play necessary for any slight lateral adjustments of the roll is afforded. The devices employed for effecting such lateral 90 adjustments form no part of the present invention, and hence are not described in detail herein, the same being fully set forth in my aforesaid copending application Serial 95 No. 43,132. The novel driving means for 25 the rolls, as above described, which are also employed in connection with the horizontal rolls 7, 7, are likewise made the subject of a separate copending application Serial No. 130,493, filed November 9, 1916.

Each roll is partially surrounded by a 100 water nozzle 41, providing a series of perforations for direct streams of water against the operating surface of the roll. The nozzles 41 for the vertical rolls 5 are shown in Fig. 2, the same being fixed to the walls 105 of the housing or secured in any suitable manner in the positions shown; the nozzles for the horizontal rolls 7 are not shown. In order to prevent the water discharged by 110 said nozzles upon the vertical rolls from passing into the pinion housing 1, each lower adjusting yoke 23 has a depending skirt 42, surrounding a restricted neck 43 of a water 115 guard 44, through which passes the shaft 39 of the roll. The water guard flares outwardly at the bottom, as shown at 45, in surrounding relation to the bearing for the upper end of pinion 36, so that the descending water is directed away from the interior 120 of the pinion housing.

I claim,

1. In a rolling mill, a pair of rolls having 125 opposing grooves co-operating to form a reducing pass, a fixed guide, a fixed water distributing member partially surrounding each roll and providing a plurality of water jets impinging directly upon said roll, and

means for adjusting each roll to aline its groove with said guide and with said jets.

2. In a rolling mill, a pair of rolls having opposing grooves coöoperating to form a reducing pass, a fixed guide, and a fixed water distributing member partially surrounding each roll and providing a plurality of water jets impinging directly on

its roll, in a plane coinciding substantially with the axial line of said guide. 10

Dated this sixth day of November, 1916.

VICTOR E. EDWARDS.
